US00D921587S

(12) **United States Design Patent** (10) **Patent No.:** **US D921,587 S**
(45) **Date of Patent:** **** Jun. 8, 2021**

(54) **CORE**

(71) Applicant: **SUMIDA CORPORATION**, Tokyo (JP)

(72) Inventor: **Hitoshi Moriya**, Natori (JP)

(73) Assignee: **SUMIDA CORPORATION**

(**) Term: **15 Years**

(21) Appl. No.: **29/698,498**

(22) Filed: **Jul. 17, 2019**

(30) **Foreign Application Priority Data**

Jan. 23, 2019 (JP) 2019-001232
Jan. 23, 2019 (JP) 2019-001233
Jan. 23, 2019 (JP) 2019-001234

(51) **LOC (13) Cl.** **13-02**

(52) **U.S. Cl.**

USPC **D13/117**

(58) **Field of Classification Search**

USPC D13/101, 110, 117, 118, 119, 120, 121,
D13/122, 129, 133, 153, 179, 182, 183,
D13/199

CPC H01F 27/00; H01F 27/2866; H01F 41/06
See application file for complete search history.
